his Attorneys.

UNITED STATES PATENT OFFICE.

DANIEL B. FRISBY, OF DUMONT, IOWA.

HARROW-CART.

1,385,535.

Specification of Letters Patent. Patented July 26, 1921.

Application filed January 20, 1920. Serial No. 352,699.

To all whom it may concern:

Be it known that I, DANIEL B. FRISBY, citizen of the United States, residing at Dumont, in the county of Butler and State of Iowa, 5 have invented certain new and useful Improvements in Harrow-Carts, of which the following is a specification, reference being had therein to the accompanying drawings.

This invention relates to harrow carts.

10 The object of the invention is the construction of a simple and efficient harrow cart that is attached at one end to the harrow and has at its opposite end a wheel for partly supporting the cart.

15 Another object of the invention is to improve the construction of a harrow attachment shown in the harrow attachment disclosed in my prior United States Patent, No. 991,966, issued on May 9th, 1911.

20 With these and other objects in view, my invention comprises certain novel constructions, combinations and arrangements of parts, as will be hereinafter specifically described, illustrated in the accompanying 25 drawings and more particularly pointed out in the appended claims.

In the drawings:

Figure 1 is a top plan view of a device constructed in accordance with the present 30 invention, while

Fig. 2 is a view in side elevation of the same.

Fig. 3 is a sectional view taken on line 35 3-3, Fig. 1, looking in the direction of the arrows.

Fig. 4 is a perspective view of the supporting plate.

Referring to the drawings by numerals, 1 40 designates any suitable type of a harrow, to which are attached the draft beams 2 and 3.

45 My improved harrow cart, or riding attachment, comprises a pair of arms 4; each arm 4 is bent at 5, intermediate its ends, and the lowest end 6 is flattened as at 7, and this flattened end 7 rests against the top of the beam 3. A fastening bolt 8 passes through the flattened end 7 and beam 3, securing the beam and lower flattened end of the arm together. Each arm 4 is flattened at its rear 50 end 9 in a vertical plane, and these flattened ends of the arms rest against the casting 10, and by means of bolts 11 these flattened ends 9 are secured to the casting. A rotatable frame 12 is positioned at its upper end in the casting 10, and to this frame 12 is attached 55 the wheel 13.

The arms 4 diverge from the rear ends to their forward ends with respect to each other, thereby producing a substantially Y-shaped frame.

60 The supporting plate 14 comprises a tapering body 15, and the body 15 is provided at its front end with oppositely-extending foot rests 16. In the body 15 are formed apertures 17; these apertures 17 are near the 65 outer side-edges of the body, and by reason of the body being of a tapered structure, these apertures, while arranged in pairs at the side-edges of the body, are positioned on converging lines with respect to each other, 70 so that these apertures are located contiguous to the inner sides of the arms 4 when the plate is resting upon said arms, whereby detachable fastening bolts 18 can be placed in apertures 17 of the body 15 and the lower 75 hooked end of the bolts partly surround the arms 4; nuts 19 are placed upon the upper threaded end of the bolts 18, whereby the bolts can be tightened upon the body 15 at the arms 4, holding the supporting plate 80 securely upon the Y-shaped frame, constituted by said arms 4. It will be understood that the pairs of apertures are arranged of necessity in imaginary lines of convergence to adapt these apertures for receiving the 85 bolts 18 that are snugly placed against the arms 4.

A seat standard 20 is secured, at its lower front end, upon the upper face and near the middle of the supporting plate 14, and at 90 the upper end of the seat standard is secured a seat 21; the lower end of the seat standard is accommodated on the supporting plate by reason of the body 15 being provided with a pair of apertures 22 that receive the bolts 95 23 that fasten the seat standard upon the supporting plate 14.

The peculiarly constructed supporting plate 14, together with the clamping bolts 18, produce a very efficient device that can 100 be quickly assembled with the arms 4, or quickly detached therefrom at the will of the operator; in fact the entire device can be quickly assembled or disassembled by reason of the bolted structure constituting fastening means.

105 While I have described the preferred embodiment of my invention in the foregoing description, certain minor changes or alterations may appear to one skilled in the art 110 to which this invention relates, and, therefore, I reserve the right to make such altera-

tions or changes as shall be found expedient in the manufacture of my invention on a large scale, and which changes or alterations shall fairly fall within the scope of the appended claims.

What I claim is:

1. In a device of the class described, the combination of a pair of diverging arms, a tapering plate resting upon said arms, said 10 plate comprising a flat body having at its front ends oppositely-extending foot rests, said body provided near its side edges with pairs of apertures, the pairs of apertures being formed in a converging position with 15 respect to each other, clamping bolts extending through said apertures and partly surrounding the arms, nuts on said bolts and engaging said plate for clamping the plate upon the arms, said plate provided near the 20 center of its body with a pair of apertures, a seat standard resting at its front end flat upon said plate, bolts extending through said seat standard at its front end and

through the pair of centrally-arranged apertures, a seat carried by said standard, a 25 wheel, and means for supporting said arms upon said wheel.

2. In a device of the class described, the combination with a pair of diverging arms constituting a Y-shaped frame, of a supporting plate resting upon the top of said arms, said plate provided with oppositely-extending foot rests projecting beyond the sides of the arms, clamping bolts extending 30 through the plate, said bolts having hooks 35 on their lower ends, said hooks extending around portions of said arms, said bolts arranged in pairs contiguous to the side-edges of the plate and engaging the inner faces of the arms, a seat standard carried by said 40 plate, a seat carried by said seat standard, a wheel, and means for supporting said arms upon said wheel.

In testimony whereof I hereunto affix my signature.

DANIEL B. FRISBY.
